COMBINED FINGER RING AND HANDKERCHIEF HOLDER

Bernice L. Robbins, Chicago, Ill.

Application November 4, 1952, Serial No. 22,118

Term of patent 3½ years

(Cl. D45—10)

To all whom it may concern:

Be it known that I, Bernice L. Robbins, a citizen of the United States and resident of Chicago, in the county of Cook and State of Illinois, have invented a new, original, and ornamental Design for a Combined Finger Ring and Handkerchief Holder, of which the following is a specification, reference being had to the accompanying drawings forming a part thereof.

Fig. 1 is a front elevational view of a combined finger ring and handerchief holder, showing my new design;

Fig. 2 is a top plan view thereof;

Fig. 3 is a bottom plan view thereof;

Fig. 4 is a side elevational view thereof.

I claim:

The ornamental design for a combined finger ring and handkerchief holder, substantially as shown.

BERNICE L. ROBBINS.
